CLAIM

The ornamental design for a knife handle, as shown and described.

DESCRIPTION

FIG. 1 is a front perspective view of a knife handle, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is another perspective view of the knife handle in an environmental state of use.

The broken lines depict portions of the knife handle and additional environmental structure, specifically the knife blade in FIG. 9, that form no part of the claimed design.
